UNITED STATES PATENT OFFICE.

HERMAN LEINWEBER, OF CHICAGO, ILLINOIS; CURT LEINWEBER AND FRED H. LEINWEBER EXECUTORS OF SAID HERMAN LEINWEBER, DECEASED.

AIRSHIP.

1,208,337.

Specification of Letters Patent. Patented Dec. 12, 1916.

Application filed July 21, 1914. Serial No. 852,173.

To all whom it may concern:

Be it known that I, HERMAN LEINWEBER, a citizen of the United States, and a resident of the city of Chicago, county of Cook, and 5 State of Illinois, have invented certain new and useful Improvements in Airships, of which the following is a specification.

My invention relates to improvements in airships and especially to supporting planes 10 therefor, and has for its object the provision of a plane for airships of improved construction and operation and especially designed to assist in elevating the ship and steadyng the motion of the ship on an even keel, the 15 subject matter of the present application being disclosed but not claimed in Letters Patent #1,064,232, granted applicant, June 10th, 1913.

The invention consists in the combinations 20 and arrangements of parts hereinafter described and claimed.

The invention will be best understood by reference to the accompanying drawing forming a part of this specification, and in 25 which,

Figure 1 is a side view of an airship equipped with a plane embodying my invention, and Fig. 2, an end view of the same.

The preferred form of construction as 30 illustrated in the drawing comprises a supporting plane 3 which is formed of a frame of any suitable construction and covered by canvas or other suitable material, as will be readily understood by those skilled in the 35 art. This plane is formed with its longitudinal sides or edges depressed and downwardly curved throughout the length thereof, thus forming a plane of concavo-convex shape in cross section transversely throughout its entire length. Each of the ends 4 of 40 the plane 3 is upwardly inclined for a comparatively short distance, but the concavo-convex form is retained in these upwardly inclined end portions. By this arrangement 45 of the ends of the planes, the lifting action thereof, when forced through the air in

either direction is augmented, and the travel of the ship on an even keel facilitated.

A suitable car 5 is suspended from the plane on suitable hangers 6 and suitable propellers 50 7 are arranged in a suitable frame 8 which is in turn braced and supported from car 5 and from plane 1 by means of hangers 9. Suitable power developing means is arranged in car 5 and suitable connections are made with 55 propellers 7 for driving the latter. Suitable rudders 10 are also provided for steering the ship in either direction and suitable connections are made for operating these rudders. The means for driving and controlling the 60 ship constitute the subject matter of my aforesaid Patent No. 1,064,232 and need no further description here.

While I have illustrated and described the preferred form of construction for carrying 65 my invention into effect, this is capable of variation and modification without departing from the spirit of the invention. I, therefore, do not wish to be limited to the precise details of construction set forth, but 70 desire to avail myself of such variations and modifications as come within the scope of the appended claims.

Having described my invention what I claim as new and desire to secure by Letters 75 Patent is:

An airship plane concavo-convex in transverse section throughout its length, the lower side being concave the central major portion of said plane being positioned substantially horizontally when the ship is on an even keel, and both ends thereof being upwardly inclined, substantially as described.

In testimony whereof I have signed my 85 name to this specification in the presence of two subscribing witnesses.

HERMAN LEINWEBER.
